UNITED STATES PATENT OFFICE

2,268,901

BED LAMP

Samuel L. Rubin, Chicago, Ill.

Application April 17, 1939, Serial No. 268,296

9 Claims.

(Cl. 240—52)

This invention relates to adjustable lamps designed to be used on bedsteads, although capable of general application to vertical supports such as the mirror of a bureau or other place, to be used as a reading lamp.

The object of the invention is to provide a novel lamp of the character above set forth which is adjustable at various angles especially adapting it for reading purposes while reclining in bed.

Another object of the invention is to provide a lamp composed of a few simple parts capable of economic manufacture, convenient assemblage, and ready adjustment.

Other objects and advantages will appear hereinafter and be brought out more fully in the following specification, reference being had to the accompanying drawing, wherein:

Fig. 1 is a side elevation of the adjustable lamp applied to a bedstead;

Fig. 2 is an enlarged side elevation of the lamp, partly broken away and in section;

Fig. 3 is a top plan view of Fig. 2, also partly broken away;

Fig. 4 is an enlarged section taken on line 4—4 of Fig. 2;

Fig. 5 is a vertical section taken on the line 5—5 of Fig. 3;

Fig. 6 is a horizontal section taken on the line 6—6 of Fig. 5;

Fig. 7 is a vertical section of a modification;

Fig. 8 is a horizontal section taken on the line 8—8 of Fig. 7; and

Fig. 9 is a fragmentary elevation of the bracket.

Referring more particularly to the drawing, 10 designates a bed and 11 a vertical support shown as the head of the bed to the back of which at the top, a bracket 12 is secured. This bracket comprises a plate or rectangular section of sheet metal secured in position by any suitable means such as screws 13 and having the intermediate part pressed outwardly, vertically to form a vertical open ended sleeve or bearing socket 14 which is open at the top and bottom to receive a vertical post 15 for vertical adjustment therein as will be later described. The post 15 is round or cylindrical to slide vertically for vertical adjustment up or down and turn in the sleeve or socket 14 relative to the vertical support or head 11 for horizontal lateral adjustment in an arc. The sleeve is provided with a horizontal slot 16 extending to the flanges 14a of the bracket 14. To keep the post in any desired position of vertical adjustment, it is provided with a series of spaced annular horizontal grooves 17 in the periphery thereof forming shoulders. An angular key or pin 18 having a finger or handle portion 19, fits through the slot 16 in the sleeve 14 and one of the grooves 17 in the post 15, to hold the post in any desired position and to permit quick and easy adjustment simply by removing the pin. This ad-

justment is effected by inserting the pin or key through the slot and in one of the grooves 17 in order that the post may be adjusted vertically and securely held in adjusted position. It should be noted that the lower end of the post is designed to extend through and beneath the lower end of the sleeve or socket to permit the necessary adjustment.

The post is provided with a horizontal forwardly extending portion or bracket arm 20 extending substantially at right angles to the vertical portion and then a reduced vertically extending portion 21 forming a pivot or pin bearing having a shoulder 22 formed at the bottom of the reduced portion. The opposed semi-circular ends 23 of a clamp 24 fit on the reduced portion 21 and may be swung horizontally at any angle if desired thus giving two horizontal adjustments in arcs. The clamp comprises a pair of jaws or strips 25 of spring metal having concaved or semi-spherical sockets 26 at the opposite ends and are connected intermediately through opposed registering apertures by a bolt 27. The semi-spherical portions 26 which are pressed out from the metal of the strips at the ends opposite the semi-circular ends 23 engage a ball or spherical portion 28 for universal movement thereon as frictionally gripped. This connection includes a reduced intermediate neck portion 29 and an adjacent flange 30 formed with a threaded shank or end 31 adapted to be engaged by a cap nut 32 when extended through a hole in the wall 33 of a lamp shade 34. This lamp shade is shown as of the cylindrical type made of sheet metal and open longitudinally at the bottom as indicated at 35. The ends 36 of the shade are in the form of discs flanged to receive the ends of the wall 33 and one end forms a support for a lamp socket 37 to take an electric bulb 38 and has a switch 39 axially at the outside leading to a lamp cord 40 carrying a plug 41 at its free end for insertion in a wall socket.

A lamp of the construction described is not only capable of two angular adjustments horizontally at the post or reduced bearing portion 21, but vertical adjustment at the bracket on the vertical support or head of the bed and angular adjustment horizontally and forwardly and rearwardly on the vertical axes as well as at an inclination to either side of the universal bearing as a pivot axis particularly in the manner disclosed in the dotted line positions shown in Figs. 2 and 3 of the drawing. Moreover, the lamp will stay in any adjusted position and will obviate the possibility of getting loose and falling off of the support or head of the bed as is common with the usual bed lamps. This is particularly true where a clamp is used to apply a lamp to a bedstead or to the vertical support such as the mirror frame of a dresser or bureau or the like which

is rounded at the top. The impracticability of such lamps has been a constant annoyance to users and the difficulties encountered in connection therewith have been entirely eliminated by the present construction.

In the form shown in Figs. 7 and 8 of the drawing, the construction is the same as heretofore described except that the sleeve bearing or socket 42 corresponding to the open ended sleeve bearing or socket 14 is closed at the bottom by turning the metal inwardly at right angles to the out-pressed portion of the sheet metal as indicated at 43 to take a rod or post 44 which is supported on the bottom 43, but which is incapable of vertical adjustment except above said bottom. However, in this instance, the post has a flat side 45 which engages the wall of the vertical support or head of the bed to prevent the post from turning instead of turning as previously described. The lamp may be very easily applied to a wooden or metal frame of a bedstead or other vertical support so as to project forwardly thereof and reflect the rays downwardly at any convenient point. However, by reason of the construction shown and described, the device is particularly adapted as a bed lamp.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. An adjustable lamp comprising a bracket having a socket portion closed at the bottom, a post having a flattened portion to engage a vertical support and prevent turning of the post, a clamp held on the post and a shade having a ball and socket connection with the clamp.

2. A lamp bracket of the class described comprising a sleeve, a post mounted in the sleeve against turning and having an arm with a reduced bearing portion forming a shoulder, a clamp comprising a pair of jaws having portions held on the reduced portion of the arm and spherical bearing portions, connecting means between the jaws, a lamp shade, and a ball member detachably connected to the shade and having bearing in the spherical portions for universal movement.

3. An adjustable lamp for bedsteads or the like comprising a plate adapted for attachment to a vertical support and having an out-pressed portion forming a vertical sleeve, a post in the sleeve and having a forwardly extending bearing arm with an upwardly extending bearing, a clamp mounted on the bearing of the arm for horizontal swinging movement, a lamp shade having a detachable shank and nut with a ball and socket connection to the clamp for universal adjustment at the free end of the clamp and means to limit the turning of the post in the sleeve.

4. A lamp bracket of the class described comprising a sleeve, a post mounted in the sleeve and having an arm with an upwardly extending

reduced bearing portion forming a shoulder, a clamp comprising a pair of jaws having co-acting semi-circular portions at one end held on the reduced portion of the arm for swinging movement and semi-spherical bearing portions at the other end, clamping means between the jaws, a clamp and a ball member detachably clamped to the lamp and having universal bearing in the semi-spherical portions.

5. An adjustable lamp for bedsteads or the like comprising a plate adapted for attachment to a vertical support and having an out-pressed portion forming a vertical sleeve open at the top and closed at the bottom, a post in the sleeve resting on the bottom thereof, said post having a flat portion engaging the plate and having a forwardly extending bearing arm with an upwardly extending bearing, a clamp mounted on the bearing of the arm for horizontal swinging movement and a lamp shade universally mounted at the free end of the clamp for angular adjustment at either side or up and down.

6. An adjustable lamp comprising a socket, a post mounted in the socket and having a rigid horizontal supporting arm with an upstanding bearing portion, a clamp frictionally mounted on the bearing portion to swing horizontally and held at any angular adjusted position and a lamp including a shade mounted on the clamp with a universal joint for horizontal turning movement and horizontal and vertical angular adjustment.

7. An adjustable lamp for beds and the like comprising a vertical plate adapted for attachment to a vertical support and having a vertical socket, a post in the socket and having an integral forwardly extending bearing arm, a horizontal clamp arm mounted to turn horizontally on the free end of the bearing arm and a lamp shade universally mounted on the free end of the clamp and adapted for horizontal swinging movement and for universal adjustment at the free end thereof.

8. An adjustable lamp for beds or the like comprising a bracket plate adapted for attachment to a vertical support and having a vertical socket pressed therefrom, a vertical post in the socket and having a forwardly extending horizontal bearing arm, a support mounted on the arm and frictionally clamped to turn horizontally and remain in adjusted position and a lamp shade having a universal connection with the support for universal adjustment horizontally on a vertical axis, angularly on a horizontal axis and vertical for angular movement in inclined positions at either side.

9. A lamp of the class described including a bracket comprising a plate adapted for attachment to a bed or like vertical support and having a vertical bearing sleeve pressed therefrom, a post extending through the sleeve, a pin engaged through the sleeve and tangentially in peripheral grooves in the post to adjust the post vertically while permitting turning thereof, a horizontal clamp frictionally and removably mounted to turn on the post to swing in a horizontal plane and a lamp shade having a socket, said lamp shade having a head mounted for universal angular movement in the free end of the clamp.

SAMUEL L. RUBIN.
